UNITED STATES PATENT OFFICE.

EDWARD E. LAWLER, OF PINCKNEY TOWNSHIP, LEWIS COUNTY, NEW YORK.

VEHICLE-INDICATOR.

1,229,764.

Specification of Letters Patent. Patented June 12, 1917.

Application filed December 18, 1916. Serial No. 137,536.

To all whom it may concern:

Be it known that I, EDWARD E. LAWLER, a citizen of the United States, residing at Pinckney township, in the county of Lewis 5 and State of New York, have invented certain new and useful Improvements in Vehicle-Indicators, of which the following is a specification.

This invention relates to improvements 10 in vehicle indicators, designed particularly for use in connection with automobiles, and has for its object to provide novel, simple and cheap indicators of the class, which are disposed on the mudguards, preferably 15 at the extreme front portion of the vehicle in plain view of approaching vehicles and pedestrians. A further object is to provide right and left hand indicators of the class for indicating various turning movements 20 of a vehicle and disposing said indicators at the extreme side, as well as at the front limits of the body of the car, where their view is unobstructed by any other attachments. A further object is to provide novel 25 and simple means partially located within the car, preferably in the vicinity of the dash, for operating the said indicators independently. And a further object is to generally improve and simplify the construction and operation of mechanisms of the 30 class.

I attain these objects by the means set forth in the detailed description which follows, and as illustrated by the accompanying 35 drawings, in which—

Figure 1 is a broken side elevation of an automobile; showing one of my indicators applied and in the operated position.

Fig. 2 is a front end elevation of the car; 40 showing the right and left indicators, the full and dotted lines showing one indicator operated and the other released.

Fig. 3 is an enlarged view of the guide employed for guiding and locking the operating rod.

Fig. 4 is an enlarged view of the operating-rod and crank.

Fig. 5 is an enlarged end view of one of the indicators in the operated position.

Fig. 6 is an enlarged rear-side view of the same.

Fig. 7 is a detail view of the operating shaft; showing locking notch.

In the drawing, 2 represents the body of 55 an automobile, 3 the dash which is perfor-

rated at 4, and 5—5' are respectively the left and right front mudguards, all of which parts may be of the usual construction and arrangement.

My indicators 6—6' are made substantially alike, preferably out of sheet metal, and may be plain or ornamental, or cut into different shapes, as for example, a hand, as shown. To the back of each indicator plate is secured a rod or shaft 7, which is pivotally supported at its ends by brackets 8, the latter having loops or eyes to receive the rod 7, and having feet 8' which rest upon the top face of the mud-guards, to which the brackets may be secured in any suitable manner. The indicators 6—6' are disposed transversely on the mud-guards and the inner ends of the rods 7 are fitted with cranks 9—9', which may be adjustably secured to said rods by means of set-screws 10, so they 75 may be set in different positions relatively to the indicators. The indicators 6—6' when idle or in released position preferably lie substantially horizontally upon and parallel to the tops of the mud-guards and when 80 operated, the indicators preferably move forwardly and upwardly and assume a vertical position, as shown in Figs. 1, 2, 5 and 6. The indicators 6—6' are operated from the reclining to the upright or signal position by means of rods 11—11', the forward ends of which are pivoted to the upper ends of the cranks 9—9', and thence extend rearwardly and pass through the openings 4 in the dash 3, and also through guides or plates 90 12, which are secured to the inner side of the dash, and which have key-hole shaped openings 12' therein (see Fig. 3). The opposite ends of the rods are provided with foot-pieces 13, which may be engaged by the feet 95 of the driver of the car, for moving the rods forwardly for tilting the indicators 6—6' from the reclining to the up-right position (see full and dotted lines in Figs. 1 and 2). To hold the indicators in the upright position without requiring the continued pressure of the driver's feet, the rods 11—11' are notched near their inner ends for providing reduced portions 14, which when the rods 100 are forced forwardly drop into the narrow portions of the key-holes 12'. This serves to lock the indicators in the upright position, and when it is desirable to release the indicators, the driver lifts the foot-pieces 13 with the toe of his boot, whereupon springs 110

15 force both the rods and the indicators from the full to the dotted line position shown in Fig. 1.

By disposing the indicator plates 6—6' 5 near the forward ends of the mud-guards, as shown, the view of the indicators is not obstructed by any of the lamps or other attachments usually carried by automobiles. They are also located substantially at the extreme 10 lateral margins of the vehicle and may be more readily seen than if they were disposed farther to the rear or mounted on the body of the car. In the preferred location, as shown, my indicators may be readily seen 15 at night by approaching cars, because the head-lights of the latter cast their rays upon the indicators, thus bringing them clearly into view. Furthermore, the head-lights of vehicles following an automobile equipped 20 with my indicators, also light up the rear sides of the indicators, and as they are disposed beyond the side lines of the car, as described, they are readily discernible from the rear, as well as from the front. The 25 mech. nisms which I employ for operating my indicators are extremely simple in construction and positive in operation, and the whole indicator mechanism may be produced, and applied to automobiles at a mini- 30 mum expense and they may also be applied to existing makes of vehicles of the class, without requiring alterations of either the cars or the indicating apparatus, and also without danger of disfiguring the cars.

35 Having thus described my invention, what I claim as new and desire to secure by Letters Patent, is—

1. In direction indicators for vehicles, the

combination with the mud-guard and the dash, of an indicator plate pivotally mounted 40 on the top of the mud-guard ahead of the body of the vehicle, a shaft secured to said plate, a crank adjustably secured to said shaft, a rod pivoted to said crank and piercing the dash and also a guard-plate carried 45 by the dash, said guard-plate having a key-hole and said rod having a notch for engaging the said key-hole for locking the indicator in the operated position.

2. In direction indicators for vehicles, the 50 combination with the mud-guards and the dash of a vehicle, of a pair of indicator plates mounted transversely upon said mud-guards, brackets for pivotally securing said plates to the mud-guards, cranks carried by 55 said indicator plates, independent operating rods connected to said cranks and piercing the dash, guard-plates secured to the dash having key-holes to receive said rods, and means for temporarily locking said rods at 60 the end of each forward operation.

3. In indicators for vehicles, the combination with the mud-guards and the dash of the vehicle, of a pair of plane indicators disposed transversely upon said mud-guards 65 adapted to lie horizontally and parallel to the top sides of the mud-guards when idle and to stand up-right when operated for indicating turning movements of the vehicle, brackets for pivotally supporting said indicators, a rod for operating each indicator, and means carried by the dash and pierced by said rods for locking the indicators in the upright position.

In testimony whereof I affix my signature. 75
EDWARD E. LAWLER.
